G. DAYTON & A. MALLORY.
WHIP ENGINE FOR TURNING WHIP STOCKS.

Patented Apr. 27, 1832

Apr 27, 1832

Biles Dayton & Andrew Mallory, Citizens of the United States
Setters Patent.

Dated April 27th 1832.

The Schedule referred to in these Setters Patent, and making part of the same, containing a description in the words of the said Biles Dayton & Andrew Mallory themselves, of their improvement in the Whip Engine for turning Whip stocks.

The Whip Engine is made of wood, and plated with iron, or any other metal, in the places exposed to friction, or may be made all of metal; and is constructed in the following manner, viz.

First say, a stick or piece of timber $2\frac{1}{2}$ inches square, and 2 feet in length, called the Jack; at one end of which is attached a smaller piece, called the slide, of about 16 inches long, 3 inches wide and 1 inch thick, placed transversely, and fastened by bolts or tenons, so as to turn with the said slide, which forms the front part projecting about 1 inch from the lower edge of the Jack piece, that it may fall into a groove prepared in it, and in which it moves back and forth to any distance, required, during its operation; on the under side of the Jack in a lateral direction, is a piece of timber of the same size but 4 or 5 inches shorter at the end, next to the slide; this piece is called the bat, and fastened to the Jack by means of a hinge or butt, so that the other end (being of equal length,) may open and shut like a tongue. The ends are reduced at the extremities, in a horizontal direction, to the thickness of about $\frac{1}{2}$ an inch, in form of tongs; these tongs are and move in grooves prepared for them, and which are so graduated, as to cause opening and shutting.

Within 5 or 6 inches of the opening end of the Jack, is placed the cutting iron, which is shaped so as to answer the double purpose of going and chiseling. The edge of cutting iron describes about the 11th part of a circle of $2\frac{1}{2}$ inches diameter. From one end of the cutting iron, is turned a shank, about 3 inches in length, and of sufficient strength to support it against the force required to perform its work.

At the place where the cutting iron is placed in the Jack, the timber is rounded till it corresponds with the circle of the edge, and an opening or mouth is made to discharge shavings or shavings. The use of the bat piece is to confine the ped, (which is always turned) to its proper position against the edge of the cutting iron; and in a

and for the same purpose, is attached (on the back side, opposite where the Cutter begins its work) are two pieces or blocks of about five inches in length, and two in breadth and one in thickness, mitered at one end of each piece; one of these pieces is fastened on the Cut stationary. The other is so placed down the jack, as that the mitres shall come together, and fastened only by a pivot at one end, so that it may move, or gradually open the miter, as the long open end short. The use of these mitered pieces is to form a support to the whip, (rod, or whatever) and keep it from receding in a horizontal direction from the cutting iron, any faster than the whip or rod, is intended to increase in size.

(The shape of what ever is turned depends on the distance, or of the grooves in which the two blocks move and by which they are governed.

• V. B. Any Engine of the above dimensions, with turner, rod or whip to any size, required, say from $\frac{1}{2}$ of an inch to 2 inches diameter, either of equal size, or tapering or of unequal swells, &c.

This engine is readily attached to any common turning lathe, and made of the mandrel, or chock to give motion to the whip, rod, &c; while the other end is placed in the engine, which moves up (directed by the grooves) till it approaches the mandrel, the whip is then taken out, and thrown in the iron back for another to be placed. The grooves being succeccable are readily adapted to the turning of Broom handles, Hoe handles, Curtain rods, Rake stakes, Umbrella staves, Chinaware, Walking canes, &c. and may be extended to almost any size.

General observations. The above described Engine or Machine for turning whips, or any thing that is long and limber, we claim to be an invention, or discovery, of our own, and not an improvement on any thing ever used for that purpose.
